UNITED STATES PATENT OFFICE.

CLARENCE O. CARRIER, OF CLEVELAND, OHIO.

ELECTRIC FUSE.

Application filed April 30, 1924. Serial No. 710,044.

To all whom it may concern:

Be it known that I, CLARENCE O. CARRIER, a citizen of the United States, residing at Cleveland, in the county of Cuyahoga and

5 State of Ohio, have invented certain new and useful Improvements in Electric Fuses, of which the following is a specification.

This invention relates to improvements in electric fuses of the type wherein a rotatable member is arranged to carry a length of

10 fuse wire and designed to be easily manipulated to actively position new lengths of wire to replace burnt out portions.

An object of this invention is to provide 15 a rotatable fuse wire carrying member wherein the wire is drawn from a supply reel and gripped between cam actuated jaws included in an arm arrangement of the fuse carrier.

20 Another object is to provide a rotatable fuse carrying member in which the jaws are automatically and positively opened at predetermined points to release portions of burnt out fuse wire.

25 A further object is to provide a device of this character wherein the rotatable fuse carrying member is manually operable by a means which also insures against inaccurate final positioning of a length of fuse wire.

30 It is also an object to provide a novel form of arm wherein the jaws are constructed to firmly grip a fuse wire and at times to be positively opened so that remaining portions of burnt fuses may be expelled.

35 It is likewise an object to provide a fuse and switch housing or box wherein unlocking of the cover or closure will simultaneously open the switch and wherein the arrangement is such as to prevent closing of the switch prior to again locking the cover in closed position.

40 Other objects will be in part obvious and in part pointed out hereinafter.

In order that the invention and its mode 45 of operation may be readily understood by persons skilled in the art, I have in the accompanying illustrative drawings, and in the following detailed description based thereon set out one possible embodiment of the same,

Figure 1 is a front elevation of the invention, the closure of the box or housing being open;

Figure 2 is an enlarged plan view of one of the rotatable fuse carrying members and 55 its associated parts;

Figure 3 is a detail view showing the structure of one of the radial jaw carrying arms;

Figure 4 is an end view of an arm as 60 shown in Figure 3;

Figure 5 is a detail perspective view of the arm shown in Figure 3;

Figure 6 is a sectional view taken substantially on the line 6—6 of Figure 3; 65

Figure 7 is a detail perspective view of the stop member by means of which the extent of rotation of the fuse carrying member is controlled.

Having more particular reference to the 70 drawing throughout which similar characters of reference designate like parts this improved electric fuse may be stated as comprising a pair of spaced rotatable fuse carrying members, each identically constructed 75 and having operative connection with fixed cam members, these cam members each mounting a pair of spaced contact blocks or plates, one being connected to one side of a feed line leading from a knife switch 80 or the like, and the other contact plug being connected to a wire leading to the house wiring system. For the sake of clearness, reference will be had in most instances to one of these members.

85 Each of these rotatable fuse carrying members is mounted upon a spindle 10, which in turn is mounted at one end in the bottom of the box or housing and at its other or outer end in a bracket 11 which in this instance is substantially U-shaped and provided with attaching feet 12 by means of which rigid connection is provided between the bracket and the housing. As shown, this rotatable fuse carrying member consists 90 of a central disc 13 made up of fibre or the like and provided with recesses extending radially and designed to snugly receive the inner ends of radial circumferentially spaced arms 14, each of which includes in 100

its structure, fuse wire gripping jaws. The inner ends of these arms 14 are secured in the recesses formed in the body portion 13 by means of additional fibre discs 15 which 5 are clamped upon opposite faces of said body portion and held in such position by means of metal discs 16 which are riveted or otherwise interconnected. Each of these arms comprises an elongated flat finger 17 whose inner end is disposed in one of said radial recesses and at this point coacts with a supporting member 18 to firmly mount a flat leaf spring 19. As is apparent in Figures 10 3 and 5, this spring 19 serves to normally 15 separate the fuse wire clamping jaws. Arranged upon and riveted or otherwise secured to the outer end of the finger 17 is a substantially L-shaped jaw member 20 which has a pair of spaced depending guide fingers or legs 21 which straddle a pivoted jaw member 22. The inner end of this pivoted jaw member 22 is connected to the supporting member 18 by means of a pin or the like 23. The outer portion 24 of this pivoted 25 30 jaw is widened from the pair of spaced guide fingers 21 to its outer end, at which point it is bent right angularly and downwardly and carries at its lower end a roller 25 or the like. In order that these arms 35 may be moved circumferentially a lever 26 is provided and designed to actuate a pawl and ratchet mechanism, the ratchet wheel 27 thereof being fixed to the upper end of the spindle 10, thus insuring its rotation. As 40 45 is apparent, this ratchet wheel includes a number of teeth corresponding to the number of radial arms and these teeth are so positioned with respect to the arms that upon movement of the lever 26 into contact with the stop or shoulder 28, a new 50 length of fuse wire will be accurately and actively positioned. The pawl 29 is yieldably engaged with the teeth under influence of a leaf spring 30. The lever 26 by means 55 60 of which the fuse carrying member is rotated, is normally retained in the position shown in Figure 1 against the stop pin 31 by means of a coil spring 32 which is tensioned upon movement of the operating lever.

The fuse wire 33 as shown in Figures 1 and 2 is drawn from a supply spool or reel 34 which is fixed to the bottom of the box or housing at a point adjacent the rotatable 55 65 fuse carrying member. This supply spool or reel carries a substantially L-shaped arm 35 having an opening so positioned as to guide the fuse wire into and between the clamping jaws of the fuse carrying member. 60 Fixed to the bottom of the box or housing is a cam member 36 adapted to coact with the arms 14 in such a manner as to grip and release the fuse wire 33 at predetermined and unvarying intervals. This cam member 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 of spaced contact blocks or plates 37 which are adapted to contact with a pair of the rollers 25 so as to complete an electric circuit, as is obvious.

The illustration of the arrangement of the parts as shown in Figure 1 is such as to permit functioning of the device. Should either of the lengths of fuse wire has been brought into active position and the device is again ready to function. With movement of this lever 26, the rollers 25 carried by the wire clamping jaws travel over the inclined or cam surface 38 and with this movement tightly grip the fuse wire and cause rotation of the supply spool or reel 34 thus providing a continuous feed of said fuse wire. While this gripping action is taking place at one side of the cam, the jaws of the other side are automatically separated under tension of the leaf spring 19 and consequently release the remaining portions of the fuse. Action of this spring to separate the wire gripping jaws is permitted through arranging the main body portion of the cam in a plane outwardly from the remaining portion of the track over which the rollers 25 pass.

Manifestly, the construction shown is capable of considerable modification and such modification as may fall within the scope of my claims, I consider within the spirit of my invention.

I claim:

1. An electrical device including a rotatable fuse carrying member, radial arms carried by said member, each arm comprising a top finger, a depending jaw at the outer end of said finger, a depending bracket adjacent the inner end of said finger, a jaw pivoted to said bracket to co-act with the depending jaw, spring means for normally separating the jaws, a depending leg carried by the pivoted jaw, and means for elevating the pivoted jaw to co-act with the depending jaw to grip a fuse wire.

2. A fuse wire gripper for an electrical device of the character described, including a fixed jaw, a pivoted jaw adapted for co-action with said fixed jaw, a spring arranged between said jaws and tending to separate them, a depending leg carried by said pivoted jaw, a roller carried by said depending leg, and a pair of depending guide fingers carried by the fixed jaw and straddling the pivoted jaw.

3. An electrical device comprising, a rotatable member, radial arms on said member, each arm consisting of an upper and lower

jaw pivoted together at their inner ends, spring means normally separating the jaws, a depending arm on the lower jaw and a roller on the lower end of the arm.

5 4. An electrical device of the character described comprising, a rotatable member, radial arms on said member, each arm having

an upper and lower jaw pivoted together at their inner ends, said lower jaw being substantially L-shaped, spring means tending to 10 separate the jaws, and guides for retaining the jaws in alinement.

In testimony whereof, I affix my signature.
CLARENCE O. CARRIER.
